CHILD'S TRAFFIC TOY

Albert Stubbmann, New Hyde Park, N.Y., assignor to Kohner Bros., Inc., East Paterson, N.J., a corporation of New York

Filed Apr. 6, 1967, Ser. No. 6,561

Term of patent 14 years

(Cl. D34—15)

FIG. 1

FIG. 2

FIG. 1 is a front perspective view of a child's traffic toy showing my new design;

FIG. 2 is a top plan view of the toy;

FIG. 3 is a left side elevational view of the toy;

FIG. 4 is a right side elevational view of the toy; and

FIG. 5 is a rear elevational view of the toy.

The bottom of the toy is flat and unornamented.

I claim:

The ornamental design for a child's traffic toy, substantially as shown and described.
